UNITED STATES PATENT OFFICE.

EDWARD G. ROWLEY, OF BELLEVILLE, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed November 30, 1923. Serial No. 677,859.

This invention relates to typewriting machines, in which it has been proposed to mount on the case-shift frame the ribbon-vibrator and means for varying the means of the ribbon-vibrator for printing in different colors or for stenciling, and to actuate such varying means by a finger-piece, at the front of the machine, mounted on a stationary part of the machine and having an operative connection with such varying means irrespective of the position of the case-shift frame. Mechanism of this character is employed in the "Underwood" portable typewriter, upon which the present improvements are based.

A feature of the present invention consists in the provision of improved ribbon-vibrator-controlling means including a finger-piece mounted on the case-shift frame and preferably positioned at the front thereof, to shift therewith, for so controlling the ribbon-vibrator as to determine the color of the typing or to render the ribbon-vibrator ineffective when a stencil is to be prepared.

As herein illustrated, each of the usual character key-levers, upon depression, acts through suitable means, such as a tongue thereon, to rock a universal bar, and thereby swing forwardly at the rear of the machine an arm for actuating the escapement mechanism. In its forward movement this arm engages and rocks a bell-crank to shift to the left a link connected to a toggle having at one end a fixed pivot and pivoted at the other end to a lever for actuating a ribbon-vibrator on the case-shift frame. The actuating lever for the ribbon-vibrator has no fixed fulcrum, and the action on the ribbon-vibrator actuating lever is determined by means of a member rockable to extreme positions to cause projections at the opposite ends thereof to enter into either one of two openings in the ribbon-vibrator actuating lever to vary the effect of the toggle, or to an intermediate position to permit idle actuation of said lever. Heretofore the controlling member has been actuated by a finger-piece mounted on a fixed part of the machine. According to the preferred form of the present invention the controlling member is provided with a forwardly-extending arm so shaped as to avoid interference with

other parts of the machine, and provided at its forward end with a finger-piece adjacent the front of one of the ribbon-spool cups on 55 which are color indications to assist in properly positioning the finger-piece.

It will be seen that the improved machine is efficient in action, and that the novel parts are simple in form, economical to manufacture, and conduce to compact arrangement in the machine.

Other features and advantages will hereinafter appear.

In the accompanying drawings, 65

Figure 1 is a diagrammatic side elevation, partly in section, illustrating the invention as applied to an Underwood portable machine.

Figure 2 is a detail view, partly in section, showing the mounting of the controller for the ribbon-vibrator-actuator means.

Figure 3 is a top plan view of so much of the machine as is necessary for the purpose of illustration.

Figure 4 is a fragmentary front elevation.

Figure 5 is a side elevation, partly in section, showing the central stiffening member and its connection with other parts of the machine.

Figure 6 is a fragmentary front elevation, showing the line-lock or means for locking the keys when the carriage is checked by the left margin-stop.

Figure 7 is a detail front elevation, showing the means for selectively controlling the actuation of the ribbon-vibrator and the connection by which the silent key operates the ribbon-vibrator.

Figure 8 is a top plan view of the device 90 for selectively controlling the movement of the ribbon-vibrator.

Figure 9 is a fragmentary side elevation, showing a detail of the back-spacer mechanism.

In the machine herein illustrated, type-keys 11 are mounted on the forward ends of key-levers 12, having notched rear ends engaging the lower edge of a vertical flange 13 of a transverse member 14, preferably in 100 the form of an angle bar; the vertical flange 13 serving as a fulcrum for said key-levers and having notches in its lower edge to maintain the proper spacing between the

key-levers. The key-levers 12 may also be guided by a comb 15 at the front of the machine. At its ends, the transverse member may be attached to frames 16 secured by 5 suitable fastening means, such as screws 17, to a main frame.

The key-levers 12 are provided with downwardly-extending fingers 18 from which studs 19 project into slots 20 in forwardly-extending arms of bell-cranks 21 pivoted on a transverse member 22 also secured to said frames 16. Upon depression of a type-key 11 the corresponding bell-crank 21 acts through a link 23 to swing a type-bar 24 about its pivot 25 in a type-segment 26 also attached to the frames 16 to cause types 27 to strike against a platen 28 rotatably mounted in a letter-feeding carriage 29. Preferably the bell-cranks 21 are pivoted on a wire 20 or rod 30, and the pivot 25 is a wire or rod on which all of the type-bars are mounted. The type-action herein described may be similar to that disclosed in the co-pending application of William A. Dobson, Serial No. 639,068, filed May 15, 1923 (now Patent No. 1,564,329, dated December 8, 1925).

The carriage 29 is supported for movement transversely of the machine by means of a rear rail 31 on which runs a roller 32, pivoted 30 on the carriage, and a front rail 33 between which and the carriage are interposed rolls 34 and 35. Said rails 31 and 33 form part of a case-shift frame 36 which is guided in its upward and downward movements by two sets of arms 37 and 38. The rear ends of said arms 37 are pivoted on standards 39 projecting upwardly from said frames 16, and the forward ends of these arms are connected with the shift frame by pivots 40. At their forward ends the arms 38 are provided with studs or pins 41 projecting into slots 42 in the sides of the shift frame 36 and are fixed, at their rear ends, on a shaft 43 journaled in the standards 39. The shift frame 45 may be supported in its normal position by means of flanges 44, on its sides, engaging set-screws 45 threaded upwardly through a horizontal flange 46 of the transverse member 14.

To shift the case-shift frame 36 upwardly from its normal position, provision may be made at each side of the machine of a shift-key 47 on a lever 48 mounted at an intermediate point on a pivot 49 carried by a bracket 50 on the adjacent frame 16 and having at its rear end a lateral projection 51 underlying the forward end of the adjacent arm 38.

At each depression of a type-key 11 a tongue 52 on the corresponding key-lever 12 depresses a universal bar 53 against the action of one or more springs 54. This bar 53 is mounted on forwardly-extending arms 55 of bell-cranks 56 fixed on a shaft 57 journaled in the frames 16. Fixed on the shaft

57 is an arm 58 which actuates a dog-rocker 59 of an escapement mechanism, which may be similar to that disclosed in the patent to G. W. Campbell, No. 1,232,972, dated March 9, 1920, and causes a step-by-step movement 70 of the carriage 29 in the letter-feeding direction.

For back-spacing the carriage provision may be made of a back-space key 60 on a lever 61 fulcrumed on the flange 13 in the 75 same manner as the key-levers 12 and guided at its forward end by the comb 15. Preferably the back-space lever 61 is provided near its front end with a depending finger 62 from which a stud 63 projects through a slot in the forward end of an intermediate lever 64 movable about a pivot 65 in a bracket 66 attached to the cross-member 22. Upon depression of the key 60 the rear end of the lever 64 rocks a bell-crank 67 about a pivot 85 68 in a bracket 69 on the cross-member 14, to actuate a link 70 and effect back-spacing by means which may be similar to the mechanism disclosed in the patent to Lee S. Burridge, No. 1,297,085, dated March 11, 1919. 90

To give greater rigidity to the machine, provision may be made of a girder 71 for the same general purpose as the girder disclosed in the patent to Lee S. Burridge, No. 1,322,530, dated November 25, 1919. The 95 girder 71 is centrally located and is suitably secured to the main frame, as by screws 72 passing through the frame and threaded into lugs 73 on arms 74 at the rear end of the girder and passing on opposite sides of the shaft 43. The girder 71 passes through a notch in the flange 13 and at its lower edge is provided with a curved finger or hook 75 to receive the shaft 57. The girder 71 is attached to the type-bar segment 26 by an 100 angle member or plate 76, of which one flange is secured by suitable means, such as screws 77, to the segment, and the other flange is secured to lugs 78 offset in opposite directions from the girder, by suitable means, such as screws 79. The girder 71 is also provided with a depending finger 80 having a slot through which the rod 30 passes, and the extreme forward end of the girder extends beneath a type-bar rest 80^a and engages the same. It will be evident that the girder 71 is so connected with various parts as to prevent relative displacement thereof. 115

Except when stenciling is to be effected, each depression of a character-key 11 causes 120 a typewriter ribbon 81 to be moved from an ineffective position to an effective position at the printing point, and when, as illustrated in the present case, a bichrome ribbon having, for example, a black field 82 and a red 125 field 83 is used the movement of the ribbon is varied to present the desired color field at the printing point. For this purpose, the ribbon 81 is threaded through eyes in the arms of a U-shaped ribbon-vibrator or car- 130

rier 84 mounted for up-and-down movement on a guide 85 secured by suitable means, such as screws 86, to a vertical bar 87, which may be unitary with the front rail. The lower 5 part of the ribbon-vibrator is at the front of the guide 85, but the upwardly-extending arms 88 of the vibrator lie to the rear of arms 89 offset forwardly at the upper part of the guide, and are guided thereon by 10 means of lugs 90 extending from the arms 88 of the vibrator 84 around the inner edges of the arms 89 of the guide. At its lower end, the vibrator 84 is guided for vertical movement by means of a stud 91 projecting 15 from the vibrator into a vertical slot 92 in the guide 85.

The stud 91 also serves to connect the vibrator 84 with an actuating lever 93 connected at an intermediate point by a pivot 20 94 to an upper arm 95 of a toggle 96 comprising also a lower arm 97 connected at its upper end by a pivot 98 to the arm 95, and connected by means of a link 99 to one arm 25 of a bell-crank 100 movable about a vertical pivot 101 on a bracket 102 fixed on the transverse member 14. The other arm of the bell-crank 100 is in the path of the arm 58 and will be actuated thereby, against the resistance of a spring 103, upon each depression 30 of the character-key.

The lever 93 has no fixed fulcrum, but preferably is provided with two openings 104 and 105 spaced longitudinally thereof, and, by rocking a suitably shaped member 106 to 35 insert the right end 107 thereof into the opening 105 to the right, the movement of the ribbon-vibrator will be such as to place the black field 82 at the printing point, and, upon moving the left end 108 of the member 40 106 into the left opening 104, the red field will be made effective. It will be seen that if the rocking member 106 is in its intermediate position the lever 93 will be moved up and down idly and the ribbon-vibrator 45 84 will be silenced. The ribbon-vibrating means just described is similar in certain respects to the mechanism disclosed in my co-pending application, Serial No. 669,447, filed October 19, 1923 (now Patent No. 50 1,619,375, dated March 1, 1927), and my co-pending application, Serial No. 666,682, filed October 5, 1923 (now Patent No. 1,610,325, dated December 14, 1926).

To support the member 106 and the lower 55 arm 97 of the toggle 96, provision may be made of a bracket 109 secured to one side of the case-shift frame 36 by suitable means, such as screws 110, passing through oppositely-extending lugs 111 and threaded into 60 the side of the case-shift frame. Secured to the bracket 109 by suitable means, such as screws 112, is a secondary bracket 113 having a horizontal flange 114 on which the member 106 is pivoted by means of a shouldered screw 115. The bracket is also provided

with an inwardly and downwardly extending arm 116 carrying a pivot 117 for the lower end of the arm 97 of the toggle.

In said application, Serial No. 669,447, the rocking member for varying the actuation of the ribbon-vibrator is controlled by means of a finger-piece mounted on the fixed frame and having such connections with the rocking member as to be effective thereon irrespective of the case-shift position of the 70 case-shift frame. According to the present invention, a finger-piece 118 for controlling the member 106 is mounted on the shift frame, and preferably such mounting is effected by means of an arm 119 properly shaped to avoid interference with other parts and projecting from the member 106 to the front of the frame 36, where it is provided with an upward extension 120 to support the finger-piece 118, provision being 75 made of red and black color indications, 121 and 122 respectively, on an adjacent ribbon-spool cup 123 preferably at the right of the case-shift frame 36. The color indications 121 and 122 are spaced apart, and the ribbon-vibrator may be caused to present either color field at the printing point in accordance 80 with the color indication opposite which the finger-piece is set, or the ribbon-vibrator may be silenced by setting the finger-piece opposite a white field 124 between the color indications 121 and 122.

Preferably, the finger-piece 118 is yieldably detained in one of its settings by means of a pin 125 projecting upwardly from the 100 arm 119 and having its upper end shaped to fit in any one of three recesses 126 in the lower face of a horizontal portion of a bracket 127 secured to the right side of the case-shift frame 36, and to ride out of said 105 recess when the finger-piece is pressed to one side, provision being made of stops 128 to be engaged by the arm when the latter is brought to its extreme positions.

There are two of such ribbon-spool cups 110 123 mounted at opposite sides of the shift-frame on brackets 129 and 130. In each of said cups 123 is a ribbon-spool 131 mounted to rotate with a fine-toothed ratchet-wheel 132 by means of an eccentric pin 133 projecting from the ratchet-wheel into a corresponding opening in the spool, the spool being preferably retained in position on said ratchet-wheel by a screw 134 threaded into a central spindle 135 fixed to said ratchet-wheel and mounted in a frame or bracket 136 attached to the adjacent side of the case-shift frame 36.

Immediately beneath each ratchet-wheel 132 is an arm 137 mounted to turn about the 125 axis of said spindle 135, and having an actuating pawl 138 connected thereto by a pivot 139 and urged into engagement with the ratchet-wheel by means of a spring 140, the ratchet-wheel also being engaged by a 130

detent pawl 141 pivoted on the lower side of the adjacent bracket 130 and urged against the ratchet-wheel preferably by means of a spring, not shown. To actuate 5 the arm 137, provision may be made of a pin 142 projecting downwardly therefrom and into a slot 143 in a lateral projection at the upper end of a lever 144 mounted on a pivot 145 on the inner side of the bracket or 10 frame 136 and connected at its lower end by a link 146 to an upright arm 147 of the adjacent bell-crank 56.

It will be seen that each spool-actuating device tends to draw the ribbon from the 15 other, and it is necessary, therefore, to render one of said devices ineffective when the other is effective. To this end, provision may be made for each of said devices of a plate 148 rotatable about the axis of the 20 spindle 135 and having two cam portions 149 and 150 to throw off the pawls associated with the adjacent ratchet-wheel, and a recess 151 between said cam portions to permit the 25 detent pawl 141 to engage the ratchet-wheel when the actuating pawl 138 is effective. The plate is also provided with a forwardly-extending arm 152 to control the position of the plate 148. The ribbon-feeding mechanism just described is in many respects similar to that disclosed in the patent to Lee S. 30 Burridge, No. 1,249,022, filed December 4, 1917, in which the forwardly-extending arms are connected by a link to render the driving and detent pawls for one spool ineffective 35 when those of the other spool are effective.

According to the present invention, however, the connection between the cam plates 148 is made at the rear of the cups 123. For this purpose provision may be made at each 40 end of the machine of a lever 153 pivoted to turn about the axis of the spindle 135 and resting on the lower horizontal part of the bracket 136. The lever may be connected with the cam-plate 148 by means of a pin 45 154 extending downwardly from the arm 152 of the cam-plate into an opening in the forward end of the lever 153, the levers 153 at the opposite sides of the machine being connected at their rear ends by means 50 of a link 155. For convenience in shifting the cam-plates 148, one of the levers 153, preferably that at the left, is extended forwardly and then upwardly to the front of the left spool cup 123, and is provided at 55 its upper end with a suitable finger-piece 156 immediately at the front of the cup. To detain the finger-piece 156 in either position in which it may be set, provision may be made of a pin 157 extending downwardly 60 from the left-hand lever 153 to engage in one of two depressions 158 in a plate 159 secured to the bottom of the adjacent bracket 136. Obviously the arrangement just described has many advantageous features, 65 inasmuch as the finger-piece 156 is the only

part exposed at the front of the ribbon-spool cups and the type-bar segment.

For locking the character-keys 11 when the carriage 29 reaches a predetermined position in its letter-feeding movement, provision may be made of a margin-stop 70 160 suitably positioned at a desired letter-space position on a rack-bar or margin-stop bar 161 slidably mounted by pin-and-slot connections 162 on brackets 163 secured to the 75 back wall 164 of the case-shift frame 36. Mounted on the inner face of said back wall 164 is a horizontal bar 165 preferably guided, at its left end, by means of a stud 166 fixed in the back wall, and extending 80 through a slot 167 in the bar, and, at its right end, by means of an arm 168 extending through an opening in the back wall to a point adjacent the right end of the margin-stop bar and connected therewith by means 85 of a pivot 169. The bar 165 is also provided with an arm 170 extending forwardly and downwardly, and both bars, 161 and 165, are urged to the right by means of a spring 171 connected to said arm and to a pin 172 on said rear wall. The margin-stop 90 160 is provided with a lug 173 to be engaged by one end of a lever 174 mounted on a pivot 175 on the rear of the carriage 29, and provided at its other end with a finger-piece 176 to shift the margin-stop-engaging end to 95 ineffective position when desired.

The portion of the key-locking mechanism, just described, is in general similar to that disclosed in the patent to G. W. Campbell, No. 1,407,982, dated February 28, 1922. In this patent the locking of the keys is illustrated as effected by moving an obstructing member into the path of the universal bar to which the escapement mechanism is actuated. According to the present invention, however, the locking of the character-keys is effected by means of a bar or member 177 slidably mounted on the transverse member 14, preferably by means of shouldered screws 178 extending through slots 179 in the bar and threaded into said transverse member. Said bar 177 is normally held in its extreme right position by means of a spring 180 attached at one end to a fixed part of the machine, and at the other end to the bar adjacent the left end thereof which normally lies immediately to the right of the path of the arm 58 through which the escapement mechanism is actuated. At the right the bar 177 is provided with an arm 181, of which the end lies in the path of the arm 170, and upon movement of the margin-stop bar 161 to the left the left end of the bar 177 will be moved into the path of the arm 58 to prevent the actuation of the universal bar 53 and consequently to lock the character-keys 11. Release of the keys 11, when desired, may be effected by depressing the finger-piece 176.

In order that marks, such as accents, may 130

be typed above letters when desired, provision may be made of a type-bar 24 and a silent key 182, or one which may be operated without causing a letter-feeding step of the carriage 29. The silent key 182 may be mounted on a key-lever 183, which is similar to the ordinary key-levers 12 but lacks the tongue 52 for depressing the universal bar 53 of the escapement mechanism. Inasmuch, however, as the ribbon-vibrator 84 is ordinarily controlled by the escapement mechanism, it is necessary to provide other means for actuating the ribbon-vibrator. To this end provision may be made of a link 184 connecting the upright arm of a bell-crank 185, for actuating the accent type-bar, with an arm 186 of a bell-crank 187 pivoted, preferably by means of a shouldered screw 188, in a horizontal flange 189 extending rearwardly from the lower edge of the arm 116 of the bracket 109. The bell-crank 187 also comprises an upwardly and forwardly extending arm 190, of which the end engages the toggle 96 at such a point that upon actuation of the silent key 182 the toggle 96 will be shifted from its Figure 4 position to its Figure 7 position, thereby actuating the ribbon-vibrator 84 in accordance with the setting of the finger-piece 118.

Variations may be resorted to within the scope of the invention, and portions of the improvements may be used without others.

Having thus described my invention, I claim:

1. In a typewriting machine, the combination of a platen and a platen-frame shiftable to case-shift positions, a bichrome ribbon-carrier on the shift frame, a ribbon-vibrator pivoted at one end to the ribbon-carrier, a bracket secured to the shift frame to support the opposite end of the ribbon-vibrator, means mounted upon the bracket and engageable with the ribbon-vibrator at different positions of its length to determine the throw of the carrier from a normal position, a toggle also mounted upon said bracket and connectible to the ribbon-carrier, a bell-crank mounted upon a stationary part of the machine, a link connecting the bell-crank and operable to straighten the toggle, and key-actuated means operative to vibrate the bell-crank to effect the shifting of a ribbon zone to the typing position.

2. In a typewriting machine, in combination, a platen, a ribbon-vibrator actuator including a lever, an actuating toggle connected at one end to said lever, a bracket on which the other end of the toggle is pivoted, a device mounted on said bracket for varying the fulcrum of said lever to vary the color of the typing, and a lever pivoted on said bracket for operating said toggle.

3. In a typewriting machine, in combination, a platen, escapement mechanism, a ribbon-vibrator actuator including a lever, an

escapement-actuated toggle connected at one end to said lever, a bracket on which the other end of the toggle is pivoted, a device mounted on said bracket for varying the fulcrum of said lever to vary the color of the typing, and a lever pivoted on said bracket for operating said toggle.

4. In a typewriting machine, in combination, a platen, a carriage therefor, a case-shift frame on the rear of which said carriage travels, ribbon-spool cups on said case-shift frame at the front and opposite sides thereof, a ribbon-vibrator on said case-shift frame, and means to vary the action of said ribbon-vibrator, comprising a member swingable about a vertical axis to cause one or the other of the color fields of a bichrome ribbon to be presented at the printing point or to an intermediate neutral position, an arm supported by said member and extending forwardly beneath one of said cups, and a finger-piece extending upwardly from said arm to the front of the cup, so that, when in neutral position, it will lie substantially in a plane passing through said vertical axis and the axis of the cup.

5. In a typewriting machine, the combination of a platen, a ribbon-vibrator-actuator including a lever, an actuating toggle connected at one end to said lever, a bracket on which the other end of the toggle is pivoted, a device mounted on said bracket to vary the fulcrum of said lever to vary the color of the typing, a lever pivoted on said bracket for operating said toggle, and a key operable to vibrate the last-named lever.

6. In a typewriting machine, the combination of a platen and a platen-frame shiftable to case-shift positions, a bichrome ribbon-carrier on the shift frame, a ribbon-vibrator-lever pivoted at one end to the ribbon-carrier, a bracket secured to the shift frame to support the opposite end of the ribbon-vibrator-lever, means mounted upon the bracket and engageable with the ribbon-vibrator-lever at different positions of its length to determine the throw of the carrier from a normal position, a toggle also mounted upon said bracket and connectible to the vibrator-carrier, a bell-crank mounted upon a stationary part of the machine, a link connecting the bell-crank and operable to straighten the toggle, and a key-actuated universal bar including an arm operative to vibrate the bell-crank to effect a ribbon-shifting movement without limiting the throw thereof.

7. In a typewriting machine, the combination of a platen and a platen-frame shiftable to case-shift positions, a ribbon-carrier mounted upon the case-shift frame, a ribbon-vibrator-lever carried by the case-shift frame and connected to said ribbon-carrier, a toggle on the shift frame and connected to the vibrator lever, and a pivot carrier movable with the shift frame and swingable at right

angles to the plane of the vibrator lever and including spaced-off pivots engageable with said lever at different positions of its length to predetermine the typing zone of the ribbon presented to the printing position.

8. In a typewriting machine, the combination of a platen and a platen-frame shiftable to case-shift positions, a ribbon-carrier mounted upon the case-shift frame, a ribbon-vibrator-lever carried by the case-shift frame and connected to said ribbon-carrier, a toggle on the shift frame and connected to the vibrator lever, a pivot carrier movable with the shift frame and swingable at right angles to the plane of the vibrator lever and including two pivots each engageable with said lever at different positions of its length to predetermine the field of the ribbon presented to the printing position, and an arm formed integrally with the pivot carrier to provide for a manual control in swinging the pivots into engagement with the vibrator lever.

9. In a typewriting machine, the combination of a platen including a ribbon-carrier and a ribbon-vibrator-lever, a bracket supporting one end of said vibrator lever, means

mounted upon the bracket for varying the fulcrum of said lever to vary the color zone of the ribbon in typing, a key-actuated universal bar operable to vibrate the ribbon-vibrator-lever, and a lever pivoted on said bracket to vibrate the ribbon independently of the universal bar for typing in either color zone.

10. In a typewriting machine, the combination of a platen, a ribbon-carrier, a ribbon-vibrator-lever, means for printing an accent-mark, a bracket supporting one end of said vibrator lever, means mounted upon the bracket for varying the fulcrum of said lever to vary the color zone of the ribbon in typing, a key-actuated universal bar operable to vibrate the ribbon-vibrator-lever, a lever pivoted on said bracket to vibrate the ribbon independently of the universal bar for typing in either color zone, and a key operatively connected to said last-mentioned lever, the depression of said key being effective to operate said printing means without actuating said universal bar.

EDWARD G. ROWLEY.
